Application August 2, 1937, Serial No. 156,884

5 Claims. (Cl. 155—194)

Our invention relates to improvements in chairs or seats for use in passenger busses or coaches and other places wherein a tubular seat support is provided with upwardly extending back supports 5 which operate in conjunction with a connecting or top rail and with securing means, for detachably holding a seat-back effectively locked in position with a minimum number of bolts, screws or other securing devices.

10 The primary object of our invention is to provide a new and improved article of manufacture comprising a seat or chair, the parts of which may be easily and quickly assembled or separated for replacement, repair or other purposes.

15 Another object is to provide a new and improved chair construction in which a minimum number of bolts and screws are required for securing the several parts together.

A further object is to provide a new and improved chair construction in which no bolts or other securing devices project beyond the confines or contour of the seat or chair.

A still further object is to provide a new and improved construction of the character set forth in which the several parts may be easily and quickly interchanged or replaced.

We accomplish these and other objects by means of the improved construction and combination of parts disclosed in the drawings forming 30 a part of the present application, and in which—

Fig. 1 is a broken front elevation, partly in section, disclosing our improved construction;

Fig. 2 is an end elevation thereof; and

Fig. 3 is a broken detailed view, partly in section, disclosing several of the connecting parts separated from each other.

Referring to the drawings:

The numeral 1 is used to designate a seat support, from which the seat has been removed, 40 having upwardly extending back supports 2 at each end of the back thereof, said supports 2 being preferably of tubular construction. Suitable apertured lugs 3 are provided near the base or lower portions of said back supports 2.

45 A tubular connecting rail 4 is provided with downwardly turned ends 5 each arranged to match with the upper ends of the back supports 2, as disclosed in Fig. 1 of the drawings. Each end 5 is provided with a suitable centrally apertured plug or closure 6 which may be welded, pinned or otherwise secured permanently within the end 5 to close the same, while a suitable bolt 7 is also secured within each apertured plug 6 so as to extend axially from each end 5 of said connecting rail 4.

A suitable sleeve 8 on each end 5 is provided with a central partition 9 in turn centrally apertured as at 10 to receive the bolt 7 in a manner and for a purpose hereinafter more fully set forth. Each sleeve 8 is also provided with an inwardly 5 extending pintle 11 from which is suspended from its upper portion a back 12, as disclosed in Fig. 1 of the drawings.

In operation, the several parts are easily and rigidly connected by first moving the pintles 11 of 10 the sleeves 8 into the thimbled holes 14 in the upper portions of the ends of the back 12. The downwardly turned ends 5 of the connecting rail, 4, are next inserted into the upper ends of the sleeves 8 with the bolts 7 engaging the central apertures 15 10 in the partitions 9 of said sleeves 8. A thimble 16 is provided for each bolt 7 and rigidly held against the partition 9 by means of a suitable nut 17 which also holds said partition 9 and sleeve 8 tightly against the end 5 of the connecting rail 4. The outer diameter of the thimble 16 is less than the inner diameter of the sleeve 8 so that an annular socket is provided by said thimble 16 and sleeve 8 to effectively engage the upper end of the tubular back support 2 of the seat support 1.

With the connecting rail, 4, sleeves 8, pintles 11 and back 12 thus rigidly connected, the assembly is placed with the back 12 between the back supports 2 and the lower ends of the sleeves 8 are placed upon the upper ends of the back supports 2 and moved downwardly until the upper ends of said back supports 2 are firmly seated within the annular socket or channel between the thimble 16 and the sleeve 8. As the back portion 12 is now between the back supports 2 and is suspended from the pintles 11, the lower portion of said back 12 may easily be moved into proper alignment or relative position with the lower portions of said back supports 2 and may then be effectively and rigidly connected and secured in 40 position by means of any suitable securing devices, such, for instance, as the lag screws 18 passing through the apertured lugs 3 which may be welded or otherwise permanently secured to the lower portions of said back supports 2.

45 As the back 12 is thus secured against movement relatively to the back supports 2, which are integral with the seat support 1, it is obvious that the sleeves 8 and the connecting rail 5 are also effectively held rigidly in place as said sleeves 8 50 and rail 4 are secured to the back 12 which, in turn, is rigidly secured to the back supports 2.

By means of this improved construction it is possible to easily connect various and different finishes or types of parts, such as enameled or 55

painted back supports 2 and chromium or plated top or connecting rails 4, and to assemble or separate, for replacement, repairs or other purposes, the several parts of the construction.

- 5 Having described our invention, we claim—
1. A chair comprising a seat support having back supports extending upwardly therefrom; a connecting rail having a socket in each end for engaging the upper end of each back support; inwardly extending pintles mounted near the ends of said rail; a back pivotally suspended from said pintles; and means for securing said back to said back supports to retain said sockets in engaging relation with said supports.
15 2. A chair comprising a seat support having back supports extending upwardly at each end thereof; a connecting rail having downwardly turned ends each provided with a socket for engaging the upper end of each back support; an inwardly extending pintle mounted near each end of said rail; means for detachably securing said pintles to said rail; a back suspended at the top thereof from said pintles to permit the lower end of said back to be swung into position relatively to said back supports; and means for securing said back to said supports to retain the rail in engaging relation with said supports.
20 3. A chair comprising a seat support having tubular back supports extending upwardly therefrom; a connecting rail having downwardly turned ends, each of said ends being provided with an annular socket for engaging the upper end of each back support; an inwardly extending pintle mounted near each end of said rail; a back suspended from said pintles and between said back supports; and connecting means for connecting the lower end of said back with said supports.
25 4. A chair seat comprising a seat support hav-

ing a tubular back support extending upwardly from each end of the back thereof; a tubular connecting rail having downwardly turned ends each provided with an annular socket for engaging the upper end of each back support; an inwardly extending pintle mounted near each end of said rail; a back suspended at its upper end from said pintles to permit the lower end of said back to be moved into position relatively to the lower portion of said back supports; and securing means for securing the lower end of said back to said back supports to retain the ends of the connecting rail in engaging relation with the upper ends of said back supports.

5 5. A chair comprising a seat support having a 15 tubular back support extending upwardly from each end of the back thereof; a tubular connecting rail having downwardly turned ends matching with the upper ends of said back supports; an axially disposed bolt extending from 20 each end of said rail; a centrally partitioned sleeve detachably mounted upon each end of said rail and detachably engaging the upper end of each back support, said sleeve partition being centrally apertured to engage said bolt; means 25 for detachably securing said sleeves to said rail ends; an inwardly extending pintle on each sleeve; a back suspended at its upper portion from said pintles to permit the lower portion of said back to be positioned relatively to the lower portion of said back supports; and means for securing the lower portion of said back to the lower portions of said back supports and for holding said sleeves in engaging relation with the upper ends of said back supports.
